SLIDE FASTENER MACHINE

Stephen Antonietta, Port Richmond, Staten
Island, N. Y.

Application January 22, 1941, Serial No. 375,377

6 Claims. (Cl. 153—1)

This invention relates to the manufacture of slide fasteners.

One object of the invention is to provide for the improved, simplified manufacture of slide fasteners by a continuous machine whereby floor space is conserved and constant checking of accuracy is easily attained to avoid the production of defective slide fasteners.

Heretofore, it has been customary to make slide fasteners of ribbon or flat wire stock which was deformed to provide longitudinally spaced heads and simultaneously indented along U-shaped lines defining the headed fastener elements that were subsequently formed. A high degree of pressure was required to provide the heads and the U-shaped depressions, these being formed simultaneously for speed and accuracy. The ribbon or flat wire was then wound into rolls which were stocked away, thus completing the first stage of the manufacture. It is pertinent to state that the pressure referred to was applied by means of rolls, which were considered to give more accurate reproduction of the die portions in forming the heads than was possible with reciprocating dies, and of course extreme accuracy in the spacing of the heads was more readily assured by the use of pressure rolls. The high degree of pressure already referred to required that the rolls be quite massive and powerfully mounted so that this apparatus was expensive. Accordingly, the best plant layout called for a set of pressure rolls for several machines each of which severed the headed flat wire stock into the fastener elements along the U-shaped depressions, and clamped said elements on the stringer tape, completing the second and final stage of the process. Obviously this plant layout required that the pressure rolls be operated at very high speed, which in turn unduly increased the wear and stress thereon.

It is therefore an object of the invention to provide a machine whereby the laying up of a stock of headed wire rolls is eliminated and an even greater speed of production attained, and the cost of the machinery for the process maintained within reasonable limits, this including wear and replacement of parts.

Another object of the invention is to provide an improved machine whereby relatively light, slowly operating rolls form only the heads, and not the U-shaped depressions, with the headed wire fed directly and continuously to another station at which the manufacture is completed.

Sometimes the wire members were not fed to the pressure rolls with the extreme accuracy re-

quired and consequently many rolls of the defective headed wire would be produced and stocked away and the error would not be discovered until they were later used in forming the finished slide fastener. In practise, the latter is frequently inspected as it comes out of its machine.

It is therefore another object of the invention to avoid this difficulty and this I accomplish by using the headed wire continuously as produced, so that an inspection of the slide fastener manufactured will directly indicate whether an adjustment is needed at the pressure rolls, thus obviating defective slide fasteners and consequent waste.

Whereas the formation of the U-shaped depressions according to the first stage of manufacture was considered necessary in order to assure a reliable accurate cutting of the wire into the U-shaped fastener elements in the second stage, I discovered that this was unnecessary and could be dispensed with and improved results attained by avoiding the distortion and winding of the headed wire into rolls, and by a straight line clamping of the elements on the stringer, and by other improvements hereinafter described, including causing the pressure rolls to bear down flat on the area surrounding the head while the wire was being stretched and deformed to produce the head.

I further found that by providing a set of pressure rolls individual to each cutting and clamping station of the process and thus slowing up the heading operation, the heads produced were so much more accurate than before that a feeding device which engages the heads for gaging the feed operates with such accuracy that the initial U-shaped depression formerly caused by the pressure rolls as a guide in cutting out the fastener elements can be dispensed with, and extreme accuracy and even greater smoothness assured.

It is therefore a further object of the invention to provide an improved process which shall embody all the observations noted, and avoid the difficulties while assuring the advantages referred to.

Another object of the invention is to provide an improved method and machine therefore whereby the successive stages of the process can be continuously practised irrespective of any variations in speed at the corresponding stations.

Another object of the invention is to provide a machine which is of simplified, improved nature for faster operation and greater durability,

and which costs less to produce and maintain.

Other objects of the invention are to provide a machine having improved, more easily adjustable means for clamping the slide fastener elements on the stringer; improved means for mounting and feeding the stringer tape to avoid deflection of its support under strain; improved means for operating the feeding, cutting and clamping means of the second stage by using a common shaft; simplified cams and connections therefor affording a high degree of compactness and speed; and in general to provide an improved machine which is particularly adapted to develop the advantages of the new process.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawings, wherein like parts are designated by the same reference characters throughout the several views.

In the drawings:

Figure 1 is a view in side elevation with parts removed and other parts in dot-dash lines, showing a device embodying the invention.

Fig. 2 is a top plan view thereof.

Fig. 3 is a vertical sectional view taken on the line 3—3 of Fig. 4.

Fig. 4 is a vertical sectional view taken on the line 4—4 of Fig. 3.

Fig. 5 is an enlarged fragmentary view taken approximately on the line 5—5 of Fig. 2.

Fig. 6 is a bottom plan view of Fig. 5.

Fig. 7 is a sectional view on the line 7—7 of Fig. 5.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawings, therefore, are submitted merely as showing the preferred exemplification of the invention.

Referring in detail to the drawings, 10 denotes a device embodying the invention and being illustrative of the novel method hereinafter claimed. The device 10 may include a table or frame structure 11 having a top portion 12 and legs 13. On the legs at one end of the frame is suitably removably mounted a rotary shaft 14 carrying a reel 15 on which is wound a round wire 16. Carried by the top of the frame is a plate 17 on which is fixed an upright arm 18 carrying a rigid horizontal arm 19, the arms 18, 19 forming any suitable bracket. Rotatably mounted at 20 thereon is a guide roller 21 for the member 16, whereby the latter is fed to the successive wire straightening devices 22 and 23. These are exactly alike in principle and are used to eliminate kinks in the wire. Thus the device 22 comprises a series of rollers 24 mounted on a plate 25 which is affixed to the bracket arm 19, and the device 23 comprises a series of rollers 26 mounted on stub shafts 27 affixed to said arm 19. The rollers 24 afford a pressure acting on the opposite sides of the wire member 16, and the rollers 26 afford a pressure path acting on other opposite sides of the wire member 16. Both sets of staggered

rollers 24 and 26 are formed with V grooves to receive the wire.

When the wire member 16 has passed through the kink removing rollers 24 and 26, it is received in a heading mill 28, having any guides 28a for the wire at the entrance and exit thereof. The mill may comprise a support 29 and a removable support 29a fixed on the plate 17 and carrying shafts 30, 31 on which are fixed the pressure rolls 32, 33 respectively, which rotate in the directions indicated by the arrows. The rolls 32, 33 form a succession of dies, as the roll 33 is a male and the roll 32 a female member. Thus the roll 32 may have equally spaced cavities 32a in the periphery thereof, and the roll 33 may have equally spaced heads 33a in the periphery thereof to mate with the cavities 32a to thus form the succession of dies. About the cavities 32, 33 the rolls are cylindrical and are designed to flatten out the round wire member 16. This is facilitated by the working of the metal as the heads 33a push the metal into the cavities 32a in forming the heads 34 of the headed wire 35. Moreover, these heads 34 are formed with perfect accuracy, because of the angular engagement and disengagement of the die sections due to the rolling, and because the rolls clamp the wire member tightly around the head 34 that is being formed. Thus the wire is worked and considerably stiffened. Further, the rolls 32, 33 may operate at a relatively low degree of pressure, because no other deformation is being pressed out in the wire member, but only the heads 34. And finally, accuracy in a high degree is assured, because while the rolls 32, 33 operate quite rapidly, they do not function at that extreme speed heretofore required by prior processes, for reasons hereinafter apparent.

To drive the mill 28, I may provide an electric motor 36 having a pinion 37 engaging a large gear 38 on the shaft 30, which shaft carries a pinion 39 engaging a gear 40 on the shaft 31 so that both rolls 32, 33 are driven with equal power and speed.

From the mill 28, which constitutes the first station, at which the first stage of work is completed, the headed wire 35 is passed directly to the second station which comprises the unit 41 which completes the slide fastener as herein-after described. The unit 41, for the second stage of the work, is driven by independent means. If the mill 28 produces the headed wire faster than the unit 41 can use it, an automatic switch 42 cuts out the motor 36 to stop the mill. This switch 42 is operated by an arm 43 which is movably responsive to the sag or curve of the wire 35 as shown. This sag or curve is maintained so slight or at a minimum that the path of the stiffened wire may be considered to be substantially straight to avoid bending or distortion as where the headed wire was wound on reels in the prior art.

The unit 41 may comprise a drive means including a single main shaft 44 which is journaled in a plurality of hubs 45 projecting from the under side of the plate 17 which may be of varying thickness for clearance. A drive pulley 46 and a flywheel 47 may be connected to said shaft externally of the machine.

Fixed on the main shaft 44 are a plurality of like cam blocks spaced from each other. Each of these cam blocks comprises three cam portions, including an eccentric element 48 and cam portions 49 and 50 on the opposite sides of the eccentric element. The eccentric 48 are surround-

ed by the collars or arms 51 of connecting rods 52 which are of generally U-shaped form as shown in Fig. 4. Thus the lower horizontal arms form the yokes or collars 51, while the upper horizontal arms 53 are interconnected by a pin 106 for downwardly bearing on a punching or cutting head 103 as hereinafter in detail described. The cam portions 50 engage rollers 56 on the horizontal arms 57 of the L-shaped lever 58 which is pivotally mounted at 59 on a housing or wall structure 60 that is formed on the plate 17. An expansion coil spring 61 between the lever 58 and a wall 60a of the housing 60 causes the roller 56 to be maintained in engagement with its cam 50. Thus the lever 58 operates a feeding means for the headed wire 35 as hereinafter described. Rollers 62 on levers 63 follow the cam portions 49, being retained in engagement therewith by expansion coil springs 64 that bear on the levers, with the latter being pivotally mounted at 65 on the frame or housing 60. The levers 63, which oscillate in planes parallel to the drive shaft 44 carry at their upper ends opposed adjustable set screws 66 which are thus movable toward and away from each other in a common plane for operating the opposed clamping jaws 67 as hereinafter described. Also eccentrically connected to the main shaft 44 at 68 is a connecting rod 69 which leads to a tape feeding device hereinafter described. Enclosing the main shaft and the different cams and eccentrics is a crank case 70 which may be filled with lubricant.

Mounted on the plate 17 is a frame 71 which is in the form of a yoke, and the arms of which are angular as shown in Fig. 3. Formed at the apices of the arms are the bearings 72 for a shaft 73. On this shaft are fixed a taper or stringer feed roller 74 and a ratchet wheel 75. Intermediate thereof, a disc or plate 76 is freely journaled, the same carrying opposed pivotally mounted pawls 77 which are maintained in engagement with the ratchet wheel by tension coil springs 78 connected to the pawls and to the plate 76. Extending from the latter is an arm 79 connected by a universal bearing 80 with the connecting rod 69 so that rotation of the main shaft 44 causes oscillation of the plate 76 and intermittent rotation in one direction of the wheels 74 and 75. The top 81 of the yoke 71 may carry a slideable rod 82 which pivotally carries a shoe 83 pressed against the feed wheel 74 by an expansion coil spring 84 that extends around the guide rod 82. This shoe presses the stringer against the feed wheel to assure proper gripping of the stringer by the latter. If it be desired to relieve the pressure of the shoe 83, to stop the feed of the stringer, a cam lever 85 may be pivotally mounted at 86 on the rod 82, so that when the lever is swung upward the cam engages the frame portion 81 to press downward and pull up the shoe 83 against the tension of the spring 84.

By mounting the feed wheel 74 closely adjacent to the ratchet wheel and to the bearings 72, no spring of the shaft 73 will occur.

In order to assure a proper tension on the stringer, a tensioning device is provided at the lower part of the unit 41. Preferably a slot 87 having a large angular entrance is formed in the plate 17, this slot leading to a split die 88 which conforms to the shape of the stringer. One half of this die 88 is fixed on a lever 89 pivoted at 90 and actuated by a tension coil spring 91 connected to an adjustable screw comprising the head 92, whereby the tension on the spring and

hence on the die 88 is adjusted. Thus the latter can frictionally grip the stringer to produce different degrees of tension with the feed wheel 74, which rolls up the finished slide fastener.

The feeding means for the headed strip 35 comprises an L-shaped feed arm 93 disposed within a slot 94 in the lever 58. This slot 94 results in a pair of upward extending arms which form a part of the lever 58, and carry a cross pin 95 having fixed thereon a cam or eccentric 96 on which the upper end of the feed arm 93 is journaled or pivoted. Thus by turning the pin 95 the eccentric moves the feed arm 93 relative to the pivot 59 of the lever to adjust the throw of the arm during oscillation of the lever, and hence the feed is adjusted. The free end of the horizontal portion of the L-shaped arm 93 rigidly carries a hardened steel feeder head 97 whose bottom overlies the headed wire 35 and is formed with equally spaced cavities for accurately receiving the adjacent heads 34 of the headed wire 35. Accordingly, oscillation of the lever 58 causes a reciprocatory movement of the arm 93 to intermittently feed the headed wire 35 toward the right in Fig. 4, and as hereinafter more fully described.

If it be desired to lock the feed arm 93 out of engagement with the headed wire 35, as in case the stringer is being formed therein, a cam lock may be employed like that at 85. This may comprise a rod 98 connected to the feeder arm 93 and slideable in a plate 99 that is mounted on the top end of the lever 58. Pivotally mounted on the top end of the rod 98 is a cam lever 100 which may be swung upward to upwardly move the rod 99 and hence to upwardly tilt the arm 93 to clear the headed wire 35. Normally an expansion coil spring 101 acts between the plate 99 and the feed arm 93 to hold the latter down on the headed wire 35.

As shown in Figs. 3 and 7, guides 102 are provided for the headed wire 35, these guides underlying the feed arm 93, but the feed head 97 of the latter being sufficiently thin to enter between the guides to engage the heads 34 of said wire.

To punch out or cut the headed wire 35 to produce the generally U-shaped elements which are subsequently clamped around the marginal bead of the stringer, I employ a cutter head 103 which is suitably guided by means of side rails 104 and by a center post 104a integral with the members 104 and defining with the latter grooves that receive the rods 52 and the cutter 103; the members 104 being integral with the casing 60. This cutter is formed with a slot 105 to receive a pin 106 that is fixed to the connecting rods 52, while an expansion coil spring 107 acts between a top plate 103a attached to the cutter and the member 104a so as to normally maintain the pin 106 in the lower end of the slot 105. If no slide fastener elements are being cut, as in the case where the machine merely feeds the stringer, it is desirable that the cutter shall not reciprocate. In that case, the spring 107 is maintained depressed by any suitable means, not shown, and hence when the connecting rods 52 move upward they will not elevate the cutter, particularly as the vertical length of the slot 105 is greater than the path of reciprocation of the pin 106.

It will be noted that the pin 106 is offset horizontally relative to the axis of the shaft 44 so as to produce an increased delayed action at the upper and lower points in the stroke of the cutter, to afford time for the respective forward and retraction movements of the feeder head 97, in

the close relation of the parts shown. While the cam itself affords some degree of dwell, the delay is increased by the offset relation between 44 and 106 as above stated.

In order to cut out the U-shaped fastener elements, the cutter or punch 103 is formed with a groove 108 as particularly shown in Fig. 7 to afford a cutter edge to correspond to the shape of said elements. Mating with the cutter 103 is a die block 109 mounted in the frame casing 60 as clearly shown in Fig. 4, the block having an edge conforming accurately to the edge 108 and being in register therewith. The die block 109 may be retained in part by block 110, see Figs. 5 and 7, which afford an open ended keyhole slot 111 for guiding the stringer and slidably retaining the bead thereof in the head of the keyhole slot. The blocks 110 are in turn retained by plate 112, see Figs. 4 and 5. The arrangement is such that when the headed wire 35 is cut to form a slide fastener element, the latter appears and is positioned as shown at 113 and in register with the head of the keyhole slot 111 so that the stringer bead is thus directly received in the fastener element 113 between the arms thereof in position for the clamping operation.

To facilitate locking and releasing engagement between the feeder arm 93 at the head 97 thereof and the headed wire 35, a plunger 114 is mounted within the die block 109, the plunger having a downward extending rod 115 which is upwardly acted on by a compression coil spring 116. Accordingly the spring 116 elevates the plunger 114 and hence the overlying portion of the headed wire 35 so that the heads thereof are in snug engagement with the feeder arm 93. Thus the latter can feed the said wire to the cutter. But when the cutter 103 moves downward and severs an element 113, the cutter depresses the adjacent part of the headed wire 35 and hence the plunger 114 against the force of the spring 116. This depressing of the headed wire is just sufficient to disengage the heads thereof from the feeder arm 93, and the latter is simultaneously retracted. When the cutter moves upward the plunger 114 raises the headed wire back into engagement with the feeder arm 93, and the latter is simultaneously moved to feed another portion of the headed wire to the cutter 103.

It will be noted that the cutter 103 and the die 109 perform the cutting operation although the headed member has not been previously formed with a U-shaped depression as a guide or starting line for the cutter. This is rendered possible in part by extreme precision of the parts and by causing the cutter face at the right in Fig. 4 to wipe closely against the base of the head 34 of the element 35, the head being actually of somewhat conoidal form with its maximum area being at the base. By such close cutting at the base, the mass of metal forming the head facilitates a smooth, clean and accurate cut by the cutter 103 so that the results attained are as good as those obtained with the preformed U-shaped depression heretofore used.

For clamping the fastener element 113 on the stringer bead in the position of Fig. 4, the set screws 66, see Figs. 3 and 5, carried by the levers 63, actuate the clamping bars 67 which are slidably mounted in the fixed blocks 117, each bar 67 having a lower and upper jaw 118, see also Fig. 4, the upper jaws being longer and hence closer together than the lower jaws. The purpose of this arrangement is that the lower jaws 118 cause the first clamping action by squeezing

the arms of the fastener element 113 around the stringer bead; then upon the next cycle of the machine, the stringer having moved upward one step, the bars 67 upon their next reciprocation cause their upper jaws 118 to more tightly clamp the arms of the fastener element around the stringer bead and produce a final shaping thereof. For retracting the bars 67 and keeping them in contact with the set screws 66, tension coil springs 119 are connected to upright pins on the clamp bars 67 and on their adjacent levers 63.

It is seen that the clamping bars 67 move in a straight path, being always aligned with each other, and this has the important advantage that adjustment thereof is easily effected by the set screws 66. Much greater accuracy is attained as against angular adjustment heretofore used. Moreover, the clamping action along a straight line permits attainment of a high degree of clamping, with the pressure localized at the precise points desired, as against the angular clamping pressures heretofore employed. Moreover, this straight clamping pressure is peculiarly adapted for use with fastener elements 113 which have been cut without a preformed U-shaped depression in the headed wire 35, because if any roughness results due to dulling of the cutter edge, this straight line clamping pressure is better adapted to cause the jaws to press down and smooth out any roughness of the fastener elements that may result.

As the slide fastener is produced and is being wound on the feed wheel 74, the operator can readily inspect the slide fastener from time to time and ascertain whether it is wholly accurate or whether the mill 28 requires adjustment, as in the event that the heads 34 are not being formed along the true center line of the wire 35. This avoids a condition which formerly occurred where many reels of defective headed wire were produced, and the error was not discovered until the headed wire was actually used to make the slide fastener. It is also noted that since the mill 28 works in conjunction with one unit 41 it operates at less speed, assuring greater accuracy, but this in turn permits the unit 41 to operate at a higher speed than heretofore for this and the other reasons herein indicated.

Since only one main shaft 44 operates all the moving parts of the unit 41, and since all the parts as well as their motions are relatively simple, the speed of the unit 41 is greater than was heretofore possible. All the lineal movements are not in excess of approximately one sixteenth of an inch, reducing vibration and prolonging the life of the machine.

It is now seen that I have provided a highly advantageous continuous process for the manufacture of slide fasteners with the use of a relatively light mill 28 which is thus sufficiently cheap so that one can be used with each unit 41, for the respective first and second stages of the process. The mill is light because it does not require substantially more pressure than what is needed to form the heads 34, there being a resultant pressure on the areas surrounding the heads; and the mill operates more slowly because it feeds only one station or unit 41. Thus the headed wire is fed directly to the latter without requiring storage thereof and without distortion of the headed wire, while the condition of the latter as produced may be readily checked and adjusted by the customary inspection of the finished slide fastener as produced. With the other features herein described in detail, the

process is rendered operative and advantageous in a high degree.

With the process according to this invention, the mill 28 of course produces the heads facing in the proper direction for operative mounting on the stringer. In the prior art process, where the headed wire was rolled up on reels, the heads were formed in reverse direction, in other words, as if a ratchet wheel were turned around for reverse operation, the heads 34 being shaped somewhat like ratchet teeth. The slope of the heads 34 is gradual at their left and steep on the right, and this also allows for easier separation of the roll 32 from engagement of its cavities with the heads 34.

I claim:

1. A machine for making slide fasteners having U-shaped headed fastener elements spaced along a stringer on which they are clamped, including a first means for feeding a headed wire-like member step by step according to the spacing of the heads along the member, a second means for cutting said member into said U-shaped elements, a third means for clamping said elements on a stringer, a shaft, and cam means thereon including a plurality of like spaced cam blocks each having cam portions for actuating the first, second and third means.

2. A machine for making interlocking headed slide fasteners secured on stringers, including feeding means for a wire having spaced fastener heads thereon comprising an element oscillating back and forth, an arm pivotally mounted on said element and having a portion for engaging over the heads to feed the wire forward step by step according to the oscillation of said element, and means for adjusting the arm, said means cooperating with the arm and the element to vary the stroke of said feeder portion, said means including an eccentric member about the axis of the pivot of said arm, said member being rotatably adjustable.

3. A slide fastener machine including means for horizontally feeding a rod having spaced fastener heads, including an upright lever, an L-shaped arm pivotally mounted at its upper end on said lever above the pivotal mounting of the lever, the arm having a horizontal portion extending away from the lever, said horizontal portion having a head engaging portion adjacent to its free end, an eccentric at the pivot of said arm for adjusting the stroke of said head engaging portion, and means for causing oscillation of said lever.

4. A machine for making slide fasteners including means for clamping the legs of the slide fastener elements on a stringer, means for intermittently feeding said elements in one path and the stringer in a path at an angle thereto, the clamping means comprising a pair of members movable toward and away from each other, each member having at least two stepped jaws and the jaws on the different members cooperating with each other to form a plurality of clamps,

the latter being spaced along the stringer path so that one of the clamps secures an element on the stringer and the second clamp tightens said element upon advance of the secured element into register with the second clamp for a final shaping of the element, and means for actuating the clamping means synchronously with the operation of the second mentioned means.

5. A machine for making slide fasteners including a die comprising a cutter, a plunger for actuating the cutter, means for intermittently feeding to the die a wire having spaced heads so that the cutter shall sever the wire to form a succession of fastener elements to be secured to a stringer, the feeding means being movable to an inoperative position, means for feeding a stringer, reciprocatory means for actuating the plunger, lost-motion means interconnecting the plunger and the reciprocating means, said lost-motion means having a limit of relative movement between the plunger and the reciprocating means, resilient means acting between the latter and the plunger to maintain a relative position at said limit of movement such that the plunger shall be actuated by the reciprocating means to operate the cutter, said plunger being adapted to be retained against the force of the resilient means in a different position relative to the plunger so that reciprocation of the reciprocating means shall not cause actuation of the plunger, and a common means for operating the reciprocating means and the feeding means, whereby the feeding of the stringer can continue without the production of fastener elements by the cutter in the inoperative position of the feeding means.

6. A machine for making slide fasteners including a die for severing from a headed wire fastener elements to be secured to a stringer, a vertically acting plunger for actuating the die, a shaft having a cam, a connecting member directly between the cam and the plunger for causing reciprocation of the latter upon rotation of said shaft, said plunger making one reciprocation for each rotation of the cam to thus provide a dwell at the upper and lower ends of the plunger path, and means engaging the connecting member with the plunger at a point offset from the vertical plane passing through the axis of said shaft to thus provide a leverage for accentuating the dwell caused by said cam, means for feeding said wire to the die including a reciprocating head engaging member for said wire for releasably successively engaging different heads to feed the wire, and common means for operating the feeding means and the shaft, whereby the plunger affords ample dwell to permit disengagement of said heads and retraction of said member when the plunger is lowered past cutting position and to permit engagement of other heads and advance of the wire by said member when the plunger is in retracted upper position.

STEPHEN ANTONIETTA.
